UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

BOBBIN-CLEANING ATTACHMENT FOR FILLING-REPLENISHING LOOMS.

Application filed April 12, 1927. Serial No. 183,038.

This invention relates to filling replenishing looms and is more particularly directed to bobbin cleaning attachments associated with such looms for cleaning the ejected filling carriers or bobbins of waste yarn or thread during the loom operation.

In that type of filling replenishing looms wherein replenishment is effected by the change of filling carriers or bobbins in the shuttle, the ejected filling carrier contains a quantity of yarn which is left on the bobbin to insure a full pick of filling in the shed on the last flight of the shuttle preceding filling replenishment. Before such bobbins can be rewound with filling it is necessary that the waste filling thereon shall be removed, and it has heretofore been proposed to provide means for this purpose in filling replenishing looms, so that during the interval between filling replenishments the waste yarn may be withdrawn from the ejected filling carrier.

Where the bobbin cleaning element consists of a rotary member against which the filling carrier rests during the cleaning operation, the filling carrier has heretofore been supported in such position by a hinged bottom or flap which on replenishment of filling is moved for the discharge of the cleaned filling carrier or bobbin. It happens at times that the ejected filling carrier will be thrown into bobbin cleaning position before the hinged bottom or movable flap has returned to its bobbin supporting position, with the result that the bobbin still containing waste yarn will be discharged without being cleaned.

An important feature of the present invention therefore consists in providing a bobbin cleaning attachment for filling replenishing looms, wherein means are provided for catching and supporting the incoming filling carrier away from bobbin cleaning position until after the cleaned bobbin has been discharged, and thereupon permitting such incoming filling carrier to move to bobbin cleaning position after the lower movable wall or support has reached a position to prevent the discharge of such uncleaned filling carrier.

More specifically stated, the present invention provides a bobbin receiver having a bobbin cleaner against which the bobbin to be cleaned rests during the bobbin cleaning operation, and associated therewith is a

lower wall or flap which supports the bobbin in cleaning position, and to prevent the incoming bobbin from moving directly to bobbin cleaning position until after the lower wall or flap has been closed or partially closed, the present invention includes a bobbin catcher normally supported to provide a passageway for the incoming filling carrier towards cleaning position, said catcher being moved on replenishment of filling to catch and support the incoming filling carrier and then to release it for movement to bobbin cleaning position.

The invention and new combination of parts and novel features thereof will best be made clear from the following description and the accompanying drawings of one good form thereof.

In the drawings:

Fig. 1 is a perspective view of parts of a filling replenishing loom having the present invention associated therewith;

Fig. 2 is a vertical section through the bobbin receiver and associated parts, the latter being shown in their normal position during the bobbin cleaning operation; and

Fig. 3 is a similar section showing the relation of parts during replenishment of filling with the bobbin catcher closing the passageway for the incoming filling carrier towards bobbin cleaning position.

The loom frame 1 may be of usual construction and, as shown, the breast beam 2 has mounted thereon the hopper or magazine stand or support 3, the rotary member of the magazine, which may be of usual type, being supplied with filling carriers 4 containing a supply of filling.

Mounted upon the support 3 is the stud shaft 5 on which is mounted the transerrer 6 having a dog 7 which is engaged by a bunter on the lay when filling replenishment is to be effected. These parts may be of usual construction and need no further explanation since they are now well understood in the art.

Secured to the loom frame is a bracket 8 on which is mounted a support 9 for a bobbin receiver 10, the bottom of said receiver being shown as open, as at 11, so that cleaned bobbins may pass therethrough to a bobbin can 12 beneath.

The bobbin receiver 10 is provided with a shaft 13 which, as shown, extends transversely of the receiver, and has mounted

thereon the rotary bobbin cleaner 14 which is preferably provided with a roughened surface, such, for instance, as teeth 15, for engagement with the waste yarn upon the bobbin to be cleaned, and by which such waste yarn is removed from the bobbin. One end of the shaft 13 extends beyond the bobbin receiver 10, as indicated in Fig. 1, and is provided with a pulley 17 over which passes 10 a belt 18, connected with some going part of the loom, to cause rotary movement of the shaft 13 and the bobbin cleaner 14 mounted thereon while the loom is in operation.

In the present instance of the invention, 15 the belt 18 is actuated from a belt pulley 19 on the cam shaft 20 and, as indicated in Fig. 1, the pulley 19 may be conveniently formed on the hub portion of the pick cam 21, the construction being such that the rotary movement of the cam shaft 20 causes 20 rotary movement of the bobbin cleaner.

Pivottally mounted on the bobbin receiver 10 is the lower wall or flap 22 which is adjacent to the bobbin cleaner, and, as indicated in Fig. 2, serves as a support for the bobbin being cleaned, the yarn of which is engaged by the rotary bobbin cleaner and withdrawn from the bobbin. As indicated in the drawings, the bottom wall or flap 22 30 is secured to a shaft 23 which may be conveniently supported by the bobbin receiver 10.

Secured to the outwardly extending end 35 of the shaft 23 is an arm 24 through the medium of which the lower wall or flap 22 may be moved, as will presently appear, to cause the lower wall or flap to move away from the bobbin cleaner 14 in a downward direction to permit the discharge of a cleaned 40 bobbin, as indicated in Fig. 3.

Extending transversely of the bobbin receiver above the bobbin cleaner is the shaft 25 to which is secured the bobbin catcher 26, the lower end portion of which, as at 45 27, is normally maintained in proximity to the bobbin cleaner 14, to provide a passageway 28 by which the bobbin on the bobbin catcher may be directed through the passageway into bobbin cleaning position, as indicated in Fig. 2. The bobbin catcher 26 may 50 be formed either as sheet metal or of any other usual or well-known material, and is normally inclined, as indicated in Fig. 2, so that the bobbin to be cleaned and resting 55 thereon, as indicated in Fig. 3, will, when the bobbin catcher is in normal position, be directed through the passageway 28 into bobbin cleaning position. If desired, and especially when the bobbin catcher is formed 60 of metal, a stop 29 may be employed to insure that the bobbin catcher when in normal position shall rest substantially in relation to the parts as indicated in Fig. 2.

As hereinbefore stated, the bobbin catcher 65 26 is secured to the shaft 25 passing trans-

versely of the bobbin receiver, and on the outer end portion of the shaft 25 is an arm 30 of the same general character as the arm 24, but preferably longer, as indicated in Figs. 2 and 3. The arms 24 and 30 are connected for concurrent movement by a link 31 pivoted at 32 to the arm 24 and at 33 to the arm 30, the construction being such that upon movement of either of the arms 24 or 30 concurrent movement will be imparted to 70 the other arm and to the respective shafts 23 and 25 on which the lower wall 22 and the bobbin catcher 26 are secured.

In accordance with the present invention, 75 the lower wall 22 and the bobbin catcher 26 are normally positioned during weaving operation as indicated in Figs. 1 and 2, and movement thereof into the position indicated in Fig. 3 and then back to normal position is effected during replenishment of 80 filling. Mounted on the loom frame is the transverse or change shaft 34 to which is secured an arm 35 connected at 36 to a link 37 which in the present instance is pivotally connected to the arm 30 at 38, the construction being such that on rocking movement 85 of the transverse or change shaft 34, as usual in filling replenishing looms to actuate the replenishing mechanism, the bobbin wall or flap 22 and the bobbin catcher 26 will be 90 first moved from the position indicated in Fig. 2 to that indicated in Fig. 3, wherein it will be noted that the bottom wall has been moved downwardly away from the bobbin cleaner, and the bobbin catcher 26 has 95 been moved upwardly away from the bobbin cleaner to close the passageway 28, so that an incoming filling carrier cannot directly move to bobbin cleaning position. During rocking movement of the transverse 100 or rock shaft 34 in the opposite direction, however, the lower wall 22 and the bobbin catcher 26 will be returned to their normal position, as indicated in Fig. 2.

As hereinbefore noted, it is desirable that 110 the incoming filling carrier *a*, as indicated in Fig. 3, shall not be released for movement to its bobbin cleaning position until after the bottom wall or flap 22 has sufficiently moved to its initial position to prevent the discharge of the incoming filling carrier, and therefore retain it in bobbin cleaning position, a condition which is controlled by the connections between the shafts 115 23 and 25 and the actuating mechanism 120 therefor. In other words, when the parts are in position as indicated in Fig. 3, and the lower wall or flap 22 has been sufficiently opened to permit the discharge of a cleaned filling carrier or bobbin, the bobbin 125 catcher 26 is in upward bobbin holding position, and on reverse movement of the door or flap 22 and the bobbin catcher 26, the lower wall or flap 22 will be first moved sufficiently towards the bobbin cleaner to pre- 130

vent discharge of the bobbin *a* on the bobbin catcher when the latter moves towards the bobbin cleaner and opens the passageway 28 for movement of the bobbin to be cleaned to 5 cleaning position.

When filling replenishment is effected, the ejected filling carrier with the waste yarn thereon is thrown downwardly and frontwardly into the bobbin receiver, the parts 10 then being in the position indicated in Fig. 3, and in order to receive the impact of the incoming or ejected filling carrier or bobbin, it may be desirable in certain instances to provide a stop wall against which the incoming filling carrier or bobbin will impact and then drop upon the bobbin catcher. Such stop wall may be variously contrived but, as shown in the present instance, it is 15 formed of a strip of canvas 39 which may be secured at 40 near the top of the bobbin receiver and at a point 41. In the preferred construction, the lower end of the stop wall 39 is spaced from the front wall of the bobbin receiver by a spacer 42 interposed between the front of the bobbin receiver and the lower end of the stop wall 39. In the 20 present instance, the spacer 42 carries a rod about which the end of the canvas forming the stop wall 39 may be looped, as indicated, although it is obvious that any appropriate means may be employed for this 25 purpose.

The present invention, as will be noted from the construction and operation hereinbefore described, provides a bobbin cleaner in connection with which there is a bobbin catcher which is moved on replenishment of filling into bobbin catching position to close the passageway leading to the bobbin cleaning position and thereby prevent movement of the incoming filling carrier directly to cleaning position until after the bottom wall or flap 22 has been moved sufficiently towards its initial position to prevent the incoming filling carrier from being discharged. On replenishment of filling, both the bottom wall and the bobbin catcher are moved in opposite directions from the bobbin cleaner, and on the next or reverse movement of the transverse or rock shaft, these parts will again be returned to their initial position, the construction being such that the incoming filling carrier will not be released by the bobbin catcher until after the bottom wall or flap 22 is closed sufficiently towards the bobbin cleaner to prevent the incoming filling carrier which is to be cleaned from passing downwardly into the bobbin can.

60 What is claimed is:

1. In a filling replenishing loom, the combination of a transerrer for ejecting a filling carrier or bobbin from the shuttle, a bobbin receiver for the ejected filling carriers or bobbins, a rotary bobbin cleaner, a

bottom wall for supporting the bobbin in contact with the rotary cleaner, an upper wall for directing a bobbin to cleaning position, and means operated on replenishment of filling for swinging said walls in opposite direction away from the bobbin cleaner to discharge the cleaned bobbin and intercept the next bobbin to be cleaned and for then swinging said walls toward the bobbin cleaner to permit the intercepted bobbin to move to cleaning position. 70

2. In a filling replenishing loom, the combination of replenishing mechanism, a bobbin receiver having a bobbin cleaner, a pivotally mounted bottom wall for supporting a bobbin in cleaning position, a pivotally mounted upper wall for directing a bobbin to cleaning position, and means actuated on replenishment of filling for swinging the bottom wall downwardly to discharge a cleaned bobbin and the upper wall upwardly to catch a bobbin to be cleaned and then swinging the two walls toward the bobbin cleaner to permit the incoming bobbin held by the upper wall to move to cleaning position. 80

3. In a filling replenishing loom, the combination of replenishing mechanism, a bobbin receiver having a bobbin cleaner, a pivotally mounted bottom member for supporting a bobbin in cleaning position, a pivotally mounted bobbin catcher, and means actuated on replenishment of filling for swinging the bottom member and bobbin catcher in opposite directions away from the bobbin cleaner to discharge a cleaned bobbin and intercept the next bobbin to be cleaned and then moving the bottom member and catcher into initial positions that the bobbin caught by the catcher may move to cleaning position. 95

4. In a filling replenishing loom, the combination of replenishing mechanism, a bobbin receiver having a bobbin cleaner, a bottom member for supporting a bobbin in cleaning position, a bobbin catcher normally supported to provide a passageway for a bobbin to cleaning position, and means operated on replenishment of filling to cause movement of the bobbin catcher to a position closing said passageway that an incoming bobbin may be intercepted and held by the catcher and then to cause movement of the bobbin catcher to open said passageway and direct the bobbin therethrough to cleaning position. 100

5. In a filling replenishing loom, the combination of replenishing mechanism, a bobbin receiver having a bobbin cleaner, a movable bottom wall for supporting a bobbin in cleaning position, a stop wall towards which the bobbin moves when ejected by the replenishing mechanism, a pivotally mounted bobbin catcher normally supported to provide a passageway between it and the 115

- stop wall for movement of a bobbin to cleaning position, and means actuated on replenishment of filling for moving the bottom wall for the discharge of a cleaned bobbin and swinging the bobbin catcher to close the passageway that an incoming bobbin may be caught and held by the bobbin catcher and then for swinging the bobbin catcher to open the passageway that a bobbin to be cleaned may move to cleaning position.
6. In a filling replenishing loom, the combination of a replenishing mechanism, a bobbin receiver having a bobbin cleaner, a movable bottom wall for supporting a bobbin in cleaning position, a bobbin catcher normally supported to direct a bobbin to cleaning position, and means operated on replenishment of filling for moving the bottom wall for the discharge of a cleaned bobbin and moving the bobbin catcher to catch and hold an incoming bobbin and then for moving said parts in the reverse direction to effect release of the bobbin on the catcher only after the bottom wall has been moved sufficiently to prevent the discharge of the bobbin delivered by the bobbin catcher.
- 15 7. In a filling replenishing loom, the combination of replenishing mechanism, a bobbin receiver having a bobbin cleaner, a movable bottom wall for supporting a bobbin in cleaning position, a bobbin catcher normally supported to direct a bobbin to cleaning po-
- sition, a transverse or change shaft for controlling the operation of the replenishing mechanism, and connections between the transverse or change shaft, the bottom wall and bobbin catcher to operate the bottom wall and bobbin catcher to discharge a cleaned bobbin, catch and support the incoming bobbin to be cleaned and then cause the bobbin catcher to release the bobbin after the bottom wall has been moved sufficiently near its initial position to prevent the discharge of the bobbin to be cleaned.
- 16 8. In a filling replenishing loom, the combination of replenishing mechanism, a bobbin receiver having a bobbin cleaner, a stop wall in the receiver, a bobbin catcher normally supported in position to provide a passageway between the stop wall and bobbin catcher for the movement of a bobbin to cleaning position, and means actuated on replenishment of filling to cause the bobbin catcher to move towards the stop wall and close the said passageway that the bobbin catcher may catch and hold the incoming bobbin and to cause the bobbin catcher to move away from the stop wall and open the passageway for movement of the caught bobbin to bobbin cleaning position.
- 20 9. In testimony whereof, I have signed my name to this specification.

GEORGE H. WILLARD.
